UNITED STATES PATENT OFFICE.

SAMUEL J. W. RADER, OF ALFALFA COUNTY, OKLAHOMA.

AUTOMATIC AIR-HOSE COUPLER.

Application filed September 25, 1919. Serial No. 326,260.

To all whom it may concern:

Be it known that I, SAMUEL J. W. RADER, a citizen of the United States, residing in the county of Alfalfa and State of Oklahoma, have invented certain new and useful Improvements in Automatic Air-Hose Couplers, of which the following is a specification.

This invention relates to air hose couplers for railroad cars.

The object of the invention is to provide simple and efficient means for automatically connecting and disconnecting air hose of two cars.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a side elevation of a portion of two cars to be connected showing this improved coupler applied, one member of which is shown in section and the other having parts broken out.

Fig. 2 is a front end elevation of one member of the coupling, and

Fig. 3 is a rear end elevation thereof.

In the embodiment illustrated, two cars to be connected are indicated at 1 and 2, and from the bottoms of which the couplings constituting this invention depend. These couplings comprise two members 3 and 20, carried respectively by the cars 1 and 2 to be connected, and are designed for co-operation when the cars are brought together to unite the air hose of the respective cars.

The coupling member 3 comprises a truncated, hollow, cone-shaped casing 4, having an outwardly projecting, lateral flange 5 at its apex, which constitutes the rear end of the coupling, and a similar flange 5^a at its larger front end. A gasket 6 is clamped between the flange 5 of the member 4, and 50 a flange 7 carried by a tubular coupling member 8, eye bolts 9 extending through said flanges and packing as is shown clearly in Fig. 1.

A tubular shaft 10 has tapered ends 11 apertured for the passage of air there-

through, and which are designed to enter the members 8 of the two coupling elements 3 and 20. This shaft 10 has a plurality of radially extending hooks 12, three of which are here shown and which extend from about midway the length of the shaft, and are designed to form attaching elements for coiled springs 13, the other ends of which are connected by eye bolts 14 to the shell 4 near its inner end. These springs are designed to retain the shaft 10 normally in operative position and to return it to such position when it has been projected against the tension of the spring.

A collar 15 is also carried by the shaft 10 near the end, the rear of which extends through the apex of the shell 4, and is designed to limit the movement of said shaft in said shell in one direction.

The hangers 16 and 17 which support the shell 4 are here shown truncated V-shaped in form, bolted to the bottom of the car 1 and spaced apart a distance substantially equal to the length of the shell. Short coiled springs 18 are connected at one end to the front end of the shell 4, and at their other ends to the hanger 17, while similar springs 19 of greater length connect the eye bolts 9 with the hanger 16, said eye bolts thus performing a double function of suspending means for one end of the shell and as connecting means for uniting the members 8 and 4.

The other coupling member 20 is exactly like the member 3, the only difference being that the shaft 10 is not connected therewith, but is designed to move freely in relation thereto, said shaft being carried by the shell 4 on car 1, and adapted to project at its free end through the tubular member 8 of the coupler member 20 when the cars are brought together, so that the slotted end 11 thereof extends through said member 8 as shown in dotted lines in Fig. 1.

From the above description it will be obvious that when the cars 1 and 2 are brought together in coupling relation, the shaft 10 carried by car 1 will enter the large end of the coupler member 20 and pass through the corrugated tubular element 8 carried thereby, and enter the hose which is adapted to be engaged with said member 8. These members 8 are both shown corrugated peripherally, so that when a hose is slipped over them, it will be retained in engagement

therewith in the usual manner. It will also be understood that the large ends of the funnel-shaped members will contact with one another prior to the abutment of the usual draw-heads carried by the cars, thereby permitting proper yielding movement of the device to preclude the wedging or breakage of any of its parts.

The hose is not shown connected with the 10 coupler, but it is to be understood that when the cars are brought together, the pointed ends of the shaft 10 will be passed into the coupling member 8 after which the valves in the air hose will be opened manually and 15 permit the air to pass from the hose of one car through shaft 10 into the hose of the other.

From the foregoing description, taken in 20 connection with the accompanying drawings, the advantages of the construction and of the method of operation will be readily apparent to those skilled in the art to which the invention appertains and while I have described the principle of operation of the 25 invention together with the device which I now consider to be the best embodiment thereof, I desire to have it understood that the device shown is merely illustrative and that such changes may be made as are 30 within the scope of the claimed invention.

Having thus fully described my invention, what I claim as new and desire to secure by Letters Patent, is:—

1. An air hose coupler comprising a pair of cone-shaped shells adapted for abutment, 35 means for connecting a hose to the apex of each shell, brackets surrounding the shells in spaced relation thereto, radiating coiled springs connected to each shell and its respective bracket for resiliently suspending the shell, and a tubular shaft resiliently mounted in one of said shells and adapted to extend therethrough and through the other shell when the cars are in coupled relation.

2. A coupler of the class described comprising a supporting structure, a pair of spaced brackets depending therefrom, a conical open ended shell arranged within both brackets, and coiled springs radiating from opposite ends of the shell for attachment to the brackets for resiliently suspending the shell from said support.

In testimony whereof I affix my signature in presence of two witnesses.

SAMUEL J. W. RADER.
